The Washington Mills, same place.

Letters Patent No. 2,503. Dated Nov. 6-1866.

Design for a Table-Cover.

The schedule referred to in these Letters Patent and making part of the same.

To all whom it may concern:

Be it known that I, John R. Wasley, of Boston, in the County of Suffolk and State of Massachusetts, have originated and designed a new pattern for Table-Covers or other fabrics, of which the following is a full, clear and exact description, reference being had to the accompanying drawings making a part of this specification. The centre is a star surrounded by a wreath of arum leaves, radiating with scrolls and leaves, with an ornamental circle of bell-shaped objects. Encircling this is a larger wreath of flowers, composed of roses, tulips, dahlia's &c. with vase. Radiating again from the bell-shaped objects are large Indian-shaped figures, terminating at the outer edge of design, filled in with Indian figures, with intermediate bell-shaped ornaments to finish.

The colors employed for the different portions of the design, may be varied to suit the taste and wish of the manufacturer.

Claims.

I, John R. Wasley, do claim as my invention and desire to secure by Letters Patent, the design or pattern for Table-Covers or other fabrics, herein shown and set forth.
